METHOD OF LUG STRAP MANUFACTURE

Filed Feb. 23, 1938

UNITED STATES PATENT OFFICE

2,256,701

METHOD OF LUG STRAP MANUFACTURE

Henry M. Bacon, Dayton, Ohio, assignor to The Dayton Rubber Mfg. Company, Dayton, Ohio, a corporation of Ohio

Application February 23, 1938, Serial No. 192,116

11 Claims. (Cl. 139—153)

This invention relates more particularly to improvements in lug straps of laminated construction wherein superposed plies of fabric are united by a bonding material to form the strap.

Important objects of the invention are, to provide a very durable lug strap of the said character; to provide such a strap constructed for even distribution of working stress throughout the different plies of fabric; to provide for improved simplified construction of the bend or bow portion of such a strap; and to provide an improved method of making a lug strap of the said laminated type.

Other objects of the invention will appear hereinafter.

In the drawing,

Figure 1 is a perspective view of a core member employed for winding thereon a fabric sheet coated with a bonding material, as a step in lug strap manufacture;

Figure 2 a cross sectional view of the said core and showing diagrammatically the fabric wound therearound;

Figure 3 a plan view of the sleeve formed by the wound fabric, with dot and dash lines indicating the transverse severing of the sleeve to form a multitude of double straps;

Figure 4 a sectional view showing the molding of a double lug strap;

Figure 5 a transverse section on the line 5—5 of Figure 4;

Figure 6 a plan view of a molded double strap;

Figure 7 a perspective view of a finished single strap;

Figure 8 a partial sectional view similar to Figure 4, but on a central plane at a right angle thereto as at line 8—8, showing the molding of a double lug strap with integral convex cushions within its bends;

Figure 9 a detail sectional view of an end of the mold core, taken on the line 9—9 of Figure 8; and

Figure 10 a perspective view of the lug strap with such a convex cushion.

Lug straps in use heretofore have customarily been made of leather or wood, bent into shape, or of canvas duck or ticking. In the employment of the latter material it has been customary to roll the fabric spirally, cement it with glue and then bend and mold the roll so formed into the desired U form. In the employment of any of said materials the bending thereof into U-shape materially impaired their strength owing to the fact that the material at the outside

of the bend would be stretched and the material at the interior of the bend would be compressed or cramped. Consequently the lug strap would be incapable of uniformly distributed resistance to working stress and its life would be materially shortened. Particularly in the case of straps constructed of fabric and glue some layers of the fabric became stretched and others became wrinkled so that only the middle layers were in a normal condition of tension, with consequent concentration of stress and injurious strain. Efforts were made to overcome this defect but they involved laborious and costly methods of construction and failed to avoid liability of flawed construction. The employment of glue in the structure of the strap is also objectionable for the reasons that the glue tends at times to soften under the humidity of the weave room and at other times it cracks under the shocks and flexure to which the strap is subjected in service and in handling.

My invention overcomes the defects noted and provides a strong, durable lug strap by a convenient and comparatively inexpensive method for manufacturing lug straps in large quantities and with minimum liability of flawed construction. The invention also provides a lug strap made of such material as to render the strap free from attack by rodents and having other advantages which will appear hereinafter.

Further by my method of making lug straps no metal embedding reinforcing members are required. The use of metal reinforcing members and the like embedded within the strap body has a tendency to set up undue strains causing the body of the strap to segregate therefrom and accelerate the failure of the strap. Aside from this, my method avoids the necessity of using short plies of fabric, as heretofore employed in making lug straps, in order to build up thickness at desired sections of the strap. In my improved method the desired thickness is built up at the bow of the strap by heat flowing under pressure of the rubberized fabric material during molding, as hereinafter disclosed.

In the manufacture of lug straps embodying the improved construction I select a wide sheet 1 of square-woven textile fabric with maximum warp strength and with pick strength consistent with easy handling. Both sides of this sheet I coat with a bonding material 2 which is preferably a rubber composition capable of being vulcanized to a hard state and having a low viscosity prior to vulcanization. Other bonding materials having the required thermo-flowing and setting

properties may be employed but rubber is preferred, for reasons which will appear hereinafter.

The sheet 1, coated with the rubber composition is wound around a core 3 whose cross section conforms substantially to the interior of an elongated loop such as would be defined by placing two U-shaped lug straps end to end. The side edges of the core are rounded, as at 4, in accordance with the curvature of the interior of the bend or bow of the lug strap. An oak plank so formed will serve satisfactorily for the core. As the sheet is wound it is kept sufficiently taut for smoothness, and the winding is continued to form a number of superposed plies sufficient to build the structure up to a desired thickness exceeding that of the finished lug strap. The sheet should be wound with its warp threads or strands, designated W in Figure 3, running straight and parallel around the core 3. Thus the coated sheet 1 is formed into a flat, multi-ply sleeve with the plies lying smoothly one upon another. This sleeve is removed from the core 1 and severed along the transverse lines 5 equally spaced along the sleeve to thereby provide a multitude of elongated flat loops each conforming substantially to a pair of lug straps arranged end to end. Preferably the width of these partly formed double straps cut from the sleeve, that is, their width between the lines 5 is about one thirty-second of an inch less than that desired for the finished strap.

Each double strap is next subjected to a molding and preliminary vulcanizing operation. This molding and vulcanizing operation is performed to mold the strap to the desired shape and cross sectional dimensions, bond together the plies and vulcanize the rubber composition to a preliminary soft rubber state.

In preparation for the molding and vulcanizing operation a mold core 6 of steel or other suitable material is fitted into the loop defined by the double strap. This core should have precisely the shape and dimensions desired for the interior of the strap. As shown, the core has flat sides and properly rounded ends. The strap and core are placed between opposed blocks 7 of a split mold. Said blocks have in their opposed faces elongated cavities 8 with rounded ends and conform exactly to the desired shape and dimensions of the exterior of the strap. The plane of separation of the blocks occurs at the center of the bends of the strap, and the dimensions of the cavities 8 and of the core 6 are so correlated that when the mold is closed the space between the rounded ends of the core and the rounded ends of the cavities materially exceeds the space between the flat sides of the core and the flat bottoms of the cavities.

The molding operation is performed under heat and pressure to vulcanize the rubber to a preliminary, soft rubber state. Due to the shape and proportions of the parts of the mold, when the mold is closed, the flat, leg-forming portions of the strap will be subjected to greater compression than the bends of the strap, and excess bonding material will be flowed from said flat portions into the bends. Thereby the bends, while also compressed, are made thicker and less dense than the leg-forming portions. The pressure throughout the entire strap is sufficient to unite the plies intimately and evenly.

The molded double strap is next removed from the mold, the core 6 is withdrawn, the strap is cooled, and excess, overflow rubber is trimmed off. The double strap is severed in the middle

to form two single straps S. Also, the usual slots 9 are made in the legs of the strap either before or after severance. Finally the vulcanization of the rubber is completed to bring it to a hard state. This may be done by subjecting the completely formed straps to dry heat in a suitable oven.

In a modification of the above preferred method of manufacturing lug straps I may eliminate the preliminary soft rubber vulcanization step and vulcanize the double strap to a hard rubber state and thereafter sever, trim and slot the U-shaped lug strap in the usual manner. This procedure enables me to effect a decided saving in the cost of manufacturing the lug straps, however, where the highest quality of lug straps is desired the former method should be employed. It is possible, also, where the lug straps do not have to conform to exact dimensions, to form the U-shaped straps, and trim and slot them prior to vulcanizing them to a hard state.

The employment of the materials and the method described produces a superior strap which satisfies all service requirements. Hard rubber is a very satisfactory material because of its non-brittle nature, its high tensile strength, its imperviousness to weave room humidity and also because rodents will not eat it. The arrangement of the fabric with its warp threads running lengthwise of the strap contributes to tensile strength, and the manner in which the coated fabric is preformed into straps by continuous, smooth winding of the sheet 1 ensures even distribution of tension throughout all of the plies. It will be obvious that the preforming operation is performed in a manner to reduce liability of unevenness in the plies to a minimum. The usual stretching of the plies at the outside of the bow of the strap and the cramping and buckling of the plies at the inner side of the bow is entirely avoided in a simple manner by my preforming method. Substantially all fabric plies employed in the structure of the strap extend continuously throughout the length of both legs of the strap and around the bow. A desired excess thickness of the bow of the strap is obtained by flowing excess bonding material into the bow. This avoids employment of short plies of fabric to build up the thickness of the bow. The thickened bow provides the required cushioning effect. Also, while of less density than the legs of the strap the bow has adequate total strength due to its increased thickness.

Due to the fact that the fabric is coated upon both sides with the rubber composition and that the composition is confined in the molding operation the finished strap contains much more of the composition than is required for mere bonding. It comprises a large part of the strap, as shown, and forms a tough rubber body enveloping the fabric. This produces a lug strap which is hard, tough, non-friable, flexible and moisture-impervious. The rubber surrounds the individual threads of the fabric and is reinforced throughout the strap by the fabric plies.

If a plug, not shown, is required for the interior of the bow of the strap it may be fitted, drilled and riveted into place.

It is also possible to form a satisfactory convex cushion in the bow of the strap in a very simple manner. This may be done as shown in Figure 8 by provision of a mold core 6a similar to the core 6 except that it has concave ends 6b conforming to the desired shape of the cushion.

The molding pressure causes the fabric and excess bonding material to fill the concavities of the core and form the integral cushions 10. Otherwise the strap with the convex cushion is formed in precisely the same manner as the strap previously described.

This application is a continuation in part of my copending application Serial No. 68,534, filed March 12, 1936, and issued as Patent No. 2,119,479, May 31, 1938.

It is, of course, understood that my invention is not limited to the exact structure of the article disclosed and defined by the claims since obvious modifications within the scope of this invention may be made by those skilled in the art.

Having thus fully described my invention what I claim as new and desire to secure by Letters Patent is:

1. The method of making a lug strap for weaving looms, comprising providing a sheet of fabric coated with bonding material in excess of the amount required merely for bonding, winding said sheet smoothly a plurality of times around a core to produce a multi-ply sleeve conforming substantially in cross section to the elongated loop form of a pair of lug straps arranged end to end, severing said sleeve crosswise into widths approximating the width of a lug strap to thereby provide a plurality of double lug straps, inserting a mold core into the elongated loop defined by each double strap and subjecting the double strap to molding pressure directed to compress the elongated sides of the double strap normal to the plane of the plies to a greater degree than the bends of the strap forcing excess bonding material into the bends to render them thicker than the sides, severing the double strap to form single U-shaped lug straps, and curing the laminated body to form a hard integral strap.

2. The method of making a lug strap for weaving looms, comprising providing a sheet of material of a width several times that of a lug strap with bonding material, winding said sheet smoothly a plurality of times continuously around a core to produce a multi-ply sleeve conforming substantially in cross section to the elongated loop form of a pair of lug straps arranged end to end, severing said sleeve transversely into widths approximating the width of a lug strap to thereby provide a plurality of double lug straps, uniting the plies in each double lug strap by employment of a bonding material and subjecting the double strap to a molding operation so as to force bonding material to flow into the bow portions so as to build up the thickness of the double strap in the bends as compared with the interconnecting portions, severing the double strap to form single lug straps, and curing the straps to produce a tough abrasion-resistant product.

3. The method of making a lug strap for weaving looms, comprising winding plies of fabric coated with moldable material for bonding the plies in superposed relation on a core shaped to conform generally to that of a finished double lug strap and with said bonding material in excess of that required solely for bonding the plies, and then subjecting said assembly to molding pressure directed and gauged to compress the legs of the strap normal to the plane of the plies to a greater degree than the bow of the strap and force excess bonding material into the bow to render it thicker than the legs, and forming a convex cushion portion integral with the bow at the inner side of its bend.

4. The method of making U-shaped lug straps, comprising the steps of winding a rubberized sheet about a core to form a number of superposed plies thereon, removing said core therefrom from forming a sleeve and severing the superposed plies constituting said sleeve along an axis transverse to the longitudinal axis of said sleeve to form a plurality of elongated flat loops of the desired thickness, subjecting said loops to a preliminary molding and vulcanizing treatment wherein the plies are bonded together to form soft rubber loops having reinforced bow sections, said reinforced bow sections being effected by subjecting the leg portions of the strap to greater pressure than said bow sections during molding to force excess rubber to flow into the bow portions increasing the thickness of the bow portion, removing the preliminary treated loops from the mold, severing the loops in the middle, trimming and slotting them to form a plurality of U-shaped straps, and finally completing the vulcanization of the straps to a hard rubber state.

5. The method of making U-shaped lug straps, comprising the steps of winding a rubberized sheet about a core to form a number of superposed plies thereon, removing said core therefrom and severing the superposed plies along an axis transverse thereof to form an elongated flat double strap loop of the desired thickness, subjecting said loop to a preliminary molding and vulcanizing treatment wherein the plies of said double strap are bonded together to form a soft rubber loop having the bow sections thicker than the intermediate portions, said thicker bow sections being effected by subjecting the leg portions of the strap to a greater pressure than said bow section during molding to force excess rubber to flow into the bow sections, removing the preliminary treated loop from the mold, severing the loop in the middle to form two single U-shaped straps, trimming and slotting same, and finally completing the vulcanization of the U-shaped straps to a hard rubber state.

6. The method of molding a lug strap for weaving looms, comprising winding plies of square-woven textile fabric coated with excess bonding material around a core to form a sleeve conforming substantially in cross section to the elongated loop formed by a pair of lug straps arranged end to end, severing said sleeve crosswise thereof to provide a double lug strap member and molding said double strap under heat and pressure while subjecting the leg-forming portions of the strap to greater compression than the bends forcing excess bonding material from said leg-forming portions into the bends to make them thicker and less dense than said leg-forming portions.

7. The method of making lug straps for weaving looms from laminated plies of fabric coated with vulcanizable binding agent, comprising winding a rubberized sheet of fabric around a core to form an elongated loop conforming to a pair of lug straps arranged end to end of the build up plies, severing said elongated loop transversely thereof to provide a double lug strap member, molding said double strap under heat and pressure while subjecting the leg-forming portions of the strap to greater compression than the bends forcing some of the bonding material from said leg-forming portions into the bends to make them thicker and less dense than said leg-forming portions, thereafter severing the double strap in half to form two single U-shaped straps and vulcanizing the same to a hard, flexible state.

8. The method of making a lug strap for weaving looms, comprising providing a sheet of fabric coated upon both faces with bonding material, winding said sheet smoothly and lengthwise of its warp threads a plurality of times around a core to produce a multi-ply sleeve conforming substantially in cross section to the elongated loop form of a pair of lug straps arranged end to end, severing said sleeve into widths approximating the desired width of a lug strap to thereby provide a plurality of double lug straps, inserting an elongated mold core into the elongated loop defined by each double strap, subjecting the double strap to a molding operation and, in said molding operation, subjecting the elongated portions intermediate the bows of the double strap to pressure sufficient to force plies therein closer together than the plies in the bows of the strap and thereby force excess bonding material from between the plies of said intermediate portions, and causing it to flow into the bows to render the bows thicker than the sides to reinforce the same, and severing the double strap to obtain single lug straps.

9. The method of making a lug strap for weaving looms, comprising providing a sheet of fabric coated upon both faces with bonding material, winding said sheet smoothly a plurality of times around a core to produce a multi-ply sleeve conforming substantially in cross section to the elongated loop form of a pair of lug straps arranged end to end, severing said sleeve into widths approximating the desired width of a lug strap to thereby provide a plurality of double lug straps, inserting an elongated mold core into the elongated loop defined by each double strap, subjecting the double strap to a molding operation and in said molding operation subjecting the elongated sides of the double strap to pressure directed normal to the plane of the plies thereof to force said plies closer together than the plies in the bows of the strap thereby forcing excess bonding material from between the plies of said

5 sides; and causing said excess bonding material to flow between the plies of the bows, to render the bows thicker than the sides for the purpose set forth, and severing the double strap to obtain single lug straps.

10. The method of making a lug strap for weaving looms, comprising providing fabric coated upon both faces with rubber bonding material, laying said fabric in superposed plies around a core to form the legs and bow of a lug strap, arranging said fabric so that the warp threads thereof extend lengthwise of the legs and around the bow, subjecting the strap to a molding and vulcanizing operation and, in said operation, subjecting the legs of the strap to pressure directed normal to the plane of the plies in the legs to force the leg plies closer together than the plies in the bow and thereby force excess bonding material from between the leg plies, and causing said excess bonding material to flow between the plies in the bow, to render the bow thicker than the legs and provide it with more bonding material in proportion to fabric, for the purpose set forth.

15. The method of making a lug strap for weaving looms, comprising providing fabric coated with rubber bonding material in excess of the amount required merely for bonding, laying said fabric in superposed plies to form the legs and bow of a lug strap, subjecting the strap to a molding and vulcanizing operation and in said operation subjecting the legs of the strap to pressure directed normal to the plane of the plies in the legs to force them closer together than the plies in the bow thereby forcing excess bonding material from between the leg plies, and causing said excess bonding material to flow into the bow of the strap rendering the bow thicker than the legs to provide it with more bonding material in proportion to fabric, for the purpose set forth.

HENRY M. BACON.
